(57) **CLAIM**

The ornamental design for a plastic automotive shifter linkage bushing as shown and described.

DESCRIPTION

FIG. 1 is a front elevation view of a plastic automotive shifter linkage bushing, showing my new design, of which the rear elevation view, left side elevation view and right side elevation view are identical;

FIG. 2 is a top plan view thereof;

FIG. 3 is a bottom plan view thereof;

FIG. 4 is a top perspective view thereof;

FIG. 5 is a bottom perspective view thereof; and,

FIG. 6 is a cross-sectional view thereof taken along lines 6-6 in FIG. 2.

The broken lines depict cross-sectional cut indicators and form no part of the claimed design.

1 Claim, 6 Drawing Sheets
